[57] ABSTRACT

A lock fastening device comprises a pivotally mountable fastening rod or member and a retaining mechanism including a slot for receiving a length of the fastening member, one or more magnetically engageable locking tabs, and compressible elastic means for projecting the locking tabs into the receiving slot for preventing the removal of the fastening member. In a preferred arrangement, the tabs include cam surfaces so that they are forced out of the receiving slot as the fastening member is forced toward the locking position. When the rod reaches the locking position, it no longer contacts the tabs and the tabs spring back into the slot, locking the rod in position. The rod can be removed by a suitable arrangement of magnets for retracting the locking tabs from the slot. In addition, the bottom layer of the slot can include a layer of compressible elastic material for springing the rod from the locking position when the locking tabs are retracted.

KEYLESS ROD LOCKING DEVICE

BACKGROUND OF THE INVENTION

The present invention relates to a magnetic lock fastening arrangement which is particularly useful in preventing the unauthorized removal of periodicals or other printed matter from bound volumes and the theft or loss of pin-on items such as jewelry or security badges.

The unauthorized removal of periodicals or classified reports or records is a significant problem for a number of institutions such as, for example, libraries whose periodicals may be pilfered, telephone companies maintaining directories in pay phone booths and companies which maintain confidential or classified reports and records. Conventional mechanisms for locking these materials into a binder which can, in turn, be securely attached to an adjacent structure (such as a wall or a phone booth) utilize pivotally mounted elongated rods fastened by various types of mechanical locks. However, as is well known, most mechanical locks which can be obtained at reasonable expense are relatively easy to pick. A number of magnetic-type locking arrangements have been developed (see, for example, U. S. Pat. Nos. 2,730,392; 1,933,126; 3,289,443; 3,395,555; 1,686,201; and 3,095,723), but none of these are suitable for locking a pivotally mounted elongated fastening rod.

The need for better arrangements for fastening a small valuable pin or items such as jewelry and security badges is self-evident from the large number of such items lost each year. Mechanical fastening mechanisms are usually subject to accidental opening and difficult to lock.

SUMMARY OF THE INVENTION

In accordance with the invention, a lock fastening arrangement comprises a pivotally mountable fastening rod and a retaining mechanism including a slot for receiving a length of the fastening rod, one or more magnetically engageable locking tabs and compressible elastic means for projecting the locking tabs into the receiving slot for preventing the removal of the fastening rod. In a preferred arrangement, the tabs include cam surfaces so that they are forced out of the receiving slot as the rod is forced toward the locking position. When the rod reaches the locking position, it no longer contacts the tabs; and the tabs spring back into the slot, locking the rod in position. The rod can be removed by a suitable arrangement of magnets for retracting the locking tabs from the slot. In addition, the bottom layer of the slot can include a layer of compressible elastic material for springing the rod from the locking position when the locking tabs are retracted.

BRIEF DESCRIPTION OF THE DRAWINGS

The advantages, nature and various additional features of the present invention will appear more fully upon consideration of the illustrative embodiments now to be described in detail in connection with the accompanying drawings.

In the drawings:

FIG. 1 is an elevational view in partial cross section of a locking arrangement in accordance with the invention;

FIG. 2 is a cross sectional view of the retaining mechanism in FIG. 1 taken along the line 2-2;

FIG. 3 is a plan view of a portion of the structure of FIG. 1 showing the retaining mechanism in its unlocked position; and

FIGS. 4A and 4B show the end structure of a preferred fastening rod and its location with respect to the locking tabs of the retaining mechanism.

Wherever possible, the same numerals have been used to identify corresponding parts in the several drawings.

DETAILED DESCRIPTION

Referring to the drawings, FIG. 1 illustrates a lock fastening arrangement comprising a fastening rod 110 pivotally mounted on a fixed base 111, such as a metal binder. The rod may be mounted, for example, on a pin 112 extending between a pair of support members 113 and 114. A retaining mechanism 115 including a slot 116 for receiving a length of rod 110 and a pair of magnetically engageable locking tab members 117 and 118 projected into the receiving slot by a pair of elastic backing members 119 and 120, respectively, is mounted on base 111 in the arc of the fastening rod. The magnetically engageable tab members are preferably longitudinally extending ferromagnets which include transverse tabs. The ferromagnets can be made of cast or sintered Alnico (cast Alnico 1, for example, which has a residual induction of 7,750, a coercive force of 400, and a maximum energy product of 1.4), cast samarium-cobalt, or platinum-cobalt (cast or wrought). The elastic backing members 119 and 120 are preferably compressible foam rubber or a similar material and are properly dimensioned to project the tabs across the receiving slot. Advantageously, both the tab and the backing members are sealed in a housing 121 of a non-magnetic material such as aluminum.

In a preferred embodiment, the tabs include cam surfaces so that they are forced out of the receiving slot as the rod is forced toward the locking position, so that it is unnecessary to employ the magnetic key (described below) to lock the rod in place. This feature will become clear by reference to FIG. 2 which is a cross sectional view of the retaining mechanism of FIG. 1 along the line 2-2. As can be seen from the drawing, the tab members 117 and 118 include sloped cam surfaces 210 and 211, respectively, so that the insertion of rod 110 pushes them apart. In addition, the bottom of the receiving slot is preferably lined with a compressible elastic layer 212 so that when the tabs are pulled out of the slot the rod springs out of the locking position. It is clear, however, that once the rod passes the bottom of the tabs, the tabs will snap back across the slot locking the rod in position.

The method of releasing the fastening rod can be more clearly understood by reference to FIG. 3 which illustrates an open retaining mechanism. The retaining mechanism is opened with the aid of a magnetic "key" comprising an arrangement of magnets, in this case, magnets 301 and 302 adapted to retract the tabs from the channel. They effect this result by forcing the tab members against their compressible elastic backing members. The fastening rod can then be readily removed from the slot.

FIGS. 4A and 4B illustrate an alternative embodiment of a special fastening rod for use with the invention in order to produce a more foolproof lock. FIG. 4A shows a side view of the portion of the rod which fits into the retaining mechanism. This end portion is split into an upper portion 110A and lower portion 110B with sufficient space separating the two portions for the locking tabs to pass between them. The advantage of this arrangement is illustrated by FIG. 4B which schematically illustrates the rod in the locked position. In particular, it will be noted that the lower portion 110B is securely locked by tabs 117 and 118 while the upper portion 110A covers the receiving slot so that it is practically impossible to insert any device to depress the tab members and thereby release the rod.

It is in all cases understood that the above described arrangements are merely illustrative of the many possible specific embodiments which can represent applications of the principles of the invention. For example, by varying the strength, location or orientation of the magnetic poles and the compressibility of the elastic backing members, a great variety of combinations required for unlocking the device can be developed. In addition, while the device has been described as a lock for a binder or a pin-on item, it is also useful in a wide variety of other applications such as, for example, door and cabinet locks where the fastening member can be used to prevent the opening of the door. Thus, it is clear that numerous and varied other arrangements can be readily devised by those skilled in the art without departing from the spirit and scope of the invention.

I claim:

1. A lock fastening device comprising a fixed base support plate, an elongated fastening rod mounted on said fixed base plate by means of a pivotal member

secured to said base plate, said pivotal member being oriented to permit said elongated fastening rod to pivot in an arc with respect to said base plate, a non-magnetic housing means secured to said fixed base support plate, said housing including a receiving slot disposed along the arc of said elongated fastening rod, at least two locking tab members disposed within said non-magnetic housing, each locking tab member including a magnetic portion and a locking tab portion extending transverse to said receiving slot, said locking tab portions each having a cam surface adapted to force said locking tab members out of said receiving slot as said locking rod is moved into said slot, a compressible elastic means disposed within said non-magnetic housing means for projecting said tab members into said receiving slot such that said locking tab portions prevent the unauthorized removal of said fastening rod therefrom, the magnetic portion of each locking tab member being responsive to magnetic means of a predetermined configuration positioned externally of said non-magnetic housing for compressing said elastic means to thereby retract said locking tab portions from said receiving slot, said retraction of said locking tab portions freeing said fastening rod.

2. A lock fastening device according to claim 1 wherein said elongated fastening rod includes an axially extending slot, said slot dividing into two axially extending portions a section of said fastening rod, wherein said receiving slot receives the slot portion of the fastening rod, and wherein said locking tab portions each extend into said axially extending slot so that one portion of said rod covers said locking tab portions, thereby rendering unauthorized removal of said fastening device more difficult.
